CLAIM

The ornamental design for a rocking chair, as shown and described.

DESCRIPTION

FIG. 1 is a front perspective view of a rocking chair, showing my new design;

FIG. 2 is a rear perspective view thereof;

FIG. 3 is a front elevational view thereof;

FIG. 4 is a rear elevational view thereof;

FIG. 5 is a left side view thereof, the right side view being a mirror image of FIG. 5;

FIG. 6 is a top plan view thereof;

FIG. 7 is a bottom plan view thereof;

FIG. 8 is a partial enlarged view of FIG. 1;

FIG. 9 is a partial enlarged view of FIG. 2; and,

FIG. 10 is a partial enlarged view of FIG. 5.

The dot dash broken lines in FIGS. 8, 9 and 10 represents the bounds of the enlargement taken from FIGS. 1, 2 and 5 and forms no part of the claimed design. The dash-dash broken lines illustrate portions of the rocking chair that form no part of the claimed design.
